VENTILATING DEVICE

Franz J. Kurth, New York, N. Y.

Application August 7, 1937, Serial No. 157,842

1 Claims. (Cl. 98—33)

My invention relates to ventilating devices for ventilating closed spaces. The principal object of the present invention is to so design the ventilating device, that simultaneously with the exhaust of the vitiated air fresh air is supplied to the closed space, the means for exhausting the vitiated air and for supplying the fresh air being operated by the same source of energy.

In accordance with the present invention, I use two sets of fan elements each constituting a separate fan wheel, which fan wheels are preferably concentrically mounted within a casing on the shaft of an electric motor and which are so designed that by one of the fan-wheels a suction is produced whereby the vitiated air is exhausted from the closed space, whereas by the other fan-wheel fresh outside air is drawn into the closed space.

Another object of the present invention is to so distribute the fresh outside air inside the closed space as to prevent all sensation of draft being felt by the person or persons occupying the closed space. Therefore, I provide at the inner end of the casing enclosing the two fan-wheels and the motor for operating the same an air distributing device composed of a plurality of mutually spaced hollow flaring members and disposed at some distance away from the said fan-wheels so that the desired air distributing effect is obtained.

This invention is more especially adapted to be used in connection with telephone-booths, and the device embodying the invention is so designed that its parts can be readily assembled and the device as a single unit mounted in the ceiling of the telephone-booth.

When thus used for a telephone-booth, I preferably provide intermediate the fan-wheels and the air-distributor an electric light-socket adapted to receive a bulb which when switched on will heat by its radiation the surrounding air, thus creating an upward flow of the same. At the same time, thereby the heat becomes dissipated and thus is prevented from heating the telephone booth.

Preferably, the electric motor for driving the two fan-wheels and the said light-bulb are connected to the same source of electric energy in such a manner, that upon the door of the telephone-booth being closed, simultaneously the light will be switched on and the driving motor set into operation.

For a better understanding of my invention I refer to the appended drawing showing by way of example an embodiment of the invention adapted for use in connection with a telephone

booth. In the drawing, Fig. 1 is a central vertical section through the complete device shown mounted in the ceiling of a telephone-booth. Fig. 2 shows partly in elevation and partly in section the two fan elements.

As shown, the device comprises a preferably cylindrical outer casing 1 adapted to be mounted in the ceiling 2 of a telephone-booth, to which it is secured by means of bracing members shown at 3 and 3'.

Within the outer casing 1, in spaced relation thereto, is provided an inner casing shown at 4, which projects both below and above the outer casing 1 forming therewith an annular passageway 5. To the upper end of the outer casing is secured an inverted open member 6 comprising a plurality of radial arms which extend through the inner casing member 4 and, within the latter, support a small electric motor shown at 7. On the projecting shaft 8 of said motor is secured a disk 9 provided with spider arms 10 carrying at their ends a cylindrical shell 11 closely surrounding the inner casing 4, about which the said shell may rotate. By shell 11 are carried fan-blades shown at 12, whereas on the periphery of shell 11 are provided fan blades shown at 13. The fan-blades 12 are so designed that as the shell 11 rotates, they will produce an upward draft, thereby causing the air to flow upwards within the inner casing 4 in the direction of the arrows shown at a. On the other hand, the fan blades 13 provided on the periphery of shell 11 are designed to draw outside air into the passageway 5 between the inner and outer casing causing the air to flow downwards in the direction of the arrows shown at b.

At its projecting upper end, the inner casing 4 carries, or is formed with, a hood 14 which is spaced from the upper end of outer casing 1 to permit outside air to be drawn into the passageway 5 by the rotating fan-blades 13. Above the hood 14, spaced therefrom, is provided an inverted hood 15 so designed that the air drawn upwards by the fan-blades 12 will flow out without any chance of this air mingling with the outside air drawn in between the hood 14 and the upper end of the outer casing 1.

To the lower ends of the outer and inner casings 1 and 4 respectively is detachably secured an air distributing device designated D. which, as shown, comprises a plurality of mutually spaced hollow flaring members shown at 16, 17, 18, 19 and 20. These members, as will be seen, form between them flaring passageways. Through the two larger passageways formed be-

tween the outer members 16 and 17 the air, as indicated by the arrows, flows downwards into the enclosed space of the telephone booth. This is the fresh outside air drawn into the passageway 5 by the fan-blades 13 above referred to. Through the smaller passageways formed between the members 18 and 19 and 19 and 20 and through the innermost member 20, air flows upwardly through the inner casing 4 to escape at 10 the top below the inverted hood 15. This is the vitiated air, which is drawn out from the enclosed space of the telephone booth.

Within the inner casing 4, intermediate the fan-blades 12 and the air-distributor D is suspended on spider arms 21 an electric light socket shown at 22, which carries a bulb 23 extending closely down to the inner hollow members of the air distributor D. While thus the light rays emanating from the bulb 23 will be thrown downwards through the open passageways between said inner hollow members, the heat produced by the bulb will cause an initial upward flow of air and will be entirely dissipated by the increased flow generated by the revolving fan-blades 12 within the casing 4.

The spider arms 21 are fastened at their outer ends to the outer casing member 1 and extend through the inner casing member 4 into the latter where they support the lamp socket 22. These spider arms and the arms of the member 6 serve not only as supports for the lamp socket 22 and the motor 7, respectively, but cooperate with each other and with said casing members to support the inner casing member 4 within the outer casing member in desired concentric, spaced relationship thereto.

At 24 and 25 are shown stays for holding the hollow flaring members 17 and 19 and 20 in position relative to the fixed members 16 and 18.

Between the rotatable shell 11 and the outer wall of the inner casing 4 there is just enough tolerance to permit unimpeded rotation of the shell relative to said casing while practically pre-

venting any leak of air from within the inner casing 4 to the annular passageway 5, or vice versa.

While I have shown my invention as adapted for use in connection with a telephone booth, it can obviously be modified for other uses without any departure from the gist of the inventive concept.

I claim:

In a device of the character described, an outer casing, an inner casing within said outer casing and spaced therefrom to provide a passageway between said casings, said inner casing comprising separate cylindrical sections disposed in end-to-end spaced apart relationship, a rotatable cylindrical shell mounted in axial alinement with said inner casing sections and closing the space between the ends of said casing sections, the end portions of said shell being disposed in overlapping relationship to the adjacent end portions of said inner casing sections, the overlapped portions of said shell and said inner casing sections being disposed closely adjacent to each other, fan blades interiorly and exteriorly of said shell and rotatable therewith for circulating air through said inner casing and through said passageway, respectively, a plurality of arms carried by said outer casing and extending through said inner casing into the latter, a motor mounted on said arms within said inner casing and operatively connected to said shell for supporting and rotating the same, another plurality of arms carried by said outer casing at a point spaced longitudinally therealong from said first mentioned arms and extending through said inner casing into the latter, and a lamp socket mounted on said second mentioned plurality of arms within said inner casing, said first and second mentioned pluralities of arms cooperating with said casings and with each other to support said inner casing in spaced, concentric relationship to said outer casing.

FRANZ J. KURTH.
